UNITED STATES PATENT OFFICE.

WILLIAM EVENSEN, OF CHICAGO, ILLINOIS, ASSIGNOR TO THE GOSS PRINTING PRESS COMPANY, OF CHICAGO, ILLINOIS, A CORPORATION OF ILLINOIS.

PLATE-CLAMP FOR PRINTING-PRESSES.

Specification of Letters Patent.

Patented Feb. 2, 1915.

1,126,739.

Application filed May 31, 1913. Serial No. 770,695.

To all whom it may concern:

Be it known that I, WILLIAM EVENSEN, a citizen of the United States, residing at Chicago, in the county of Cook, in the State of Illinois, have invented certain new and useful Improvements in Plate-Clamps for Printing-Presses, of which the following is a specification, reference being had to the accompanying drawings.

10 This invention relates to plate clamps for printing presses and has for its object the provision of a new and improved arrangement of clamping means for securing a printing plate upon a press.

15 More particularly, this invention relates to the provision of a new and improved clamp for securing the outer edges of the inside stereotype plates upon a plate cylinder of a length to contain four or more such 20 plates. It is customary to secure the plates upon one end of a cylinder of this type independently of the plates at the other end of the cylinder, the plates at each end being secured by means of a fixed clamp at the 25 middle point of the cylinder, a slideable clamp which is loosely interposed between the inner and outer plates, and slideable clamps at the end of the cylinder adapted to be moved forcibly into engagement with 30 the outer edges of the outer plates and locked in such position, thus securing both the inner and outer plates securely in position. It is customary to provide such a cylinder with two plates circumferentially 35 of the cylinder, the two plates abreast upon one half of one end of the cylinder being locked in position independently of the other two plates abreast upon the other circumferential half of that end of the cylinder. Inasmuch as the inside plates are by this practice capable of being locked in position only 40 through the medium of the outside plates, the pressmen are unable to lock any inside plate in position upon the cylinder until its corresponding outside plate is also in position.

It is one of the objects of my invention to provide a form of slideable clamp to be interposed between the inside and the outside 50 plates such that it can be temporarily locked in position to hold one of said plates temporarily upon the cylinder until the other plate is at hand for the permanent locking of the two plates.

55 It is another object of this invention to

provide a slideable clamp of this type which can be fastened against one of the plates tightly enough to hold the plate temporarily in position, which clamp shall be free to move toward the middle of the cylinder to 60 clamp the plurality of plates abreast thereon in the old way when the permanent clamping means are operated.

It is another object of my invention to improve clamping means of this type in 65 sundry details hereinafter pointed out.

The means by which I have accomplished these objects are illustrated in the drawings and are hereinafter specifically described.

That which I believe to be new is set forth 70 in the claims.

In the drawings, Figure 1 is a side view of a cylinder provided with my new and improved system of plate clamping mechanism; Fig. 2 is an enlarged detail being a 75 longitudinal cross-section through one of my improved slideable clamps and through the portions of the cylinder adjacent thereto, being substantially an enlarged section on line 2—2 of Fig. 3; Fig. 3 is an enlarged 80 detail being substantially a cross-section through one half of the cylinder upon the line 3—3 of Fig. 2; and Fig. 4 is a perspective view of one of my improved clamps.

Referring to the several figures of the 85 drawings in which corresponding parts are indicated by the same reference characters, 10 indicates a cylinder journaled in any suitable framework by means of hubs 11 secured by means of spokes 12 concentrically 90 relative to the cylinder.

13 indicates a clamping ring extending circumferentially of the cylinder at its middle point, the edges of said clamping ring, as best shewn in Fig. 2, being beveled for 95 the reception of the beveled edges of the stereotype plates.

14 indicates stops extending longitudinally of the cylinder at opposite sides thereof, against which stops the edges of the 100 stereotype plates bear when in position upon the press. As shown in Fig. 1 the stops 14 at one end of the cylinder are located at a distance ninety degrees circumferentially of the cylinder from the strips 14 at the other 105 end of the cylinder.

In the embodiment of my improvements shown in the drawings, in which there are shown four slideable clamps interposed between each two inner and outer plates 110

mounted upon the press, I have provided only one of said four slidable clamps with my improved temporary locking means, it being clear that there are thus on the cylinder 5 four such improved clamps. These improved clamps are indicated by the numeral 15, the other of such intermediate clamps interposed between the inner and outer plates being indicated by the numeral 16. It is 10 believed that it does not make a great deal of difference which of the four intermediate clamps between each two inner and outer plates is provided with my improved temporary clamping means, but in the construction shown I have applied such improvements to one of the two clamps adapted to bear nearer the center of each plate circumferentially thereto.

17 indicates the inner plates mounted upon 20 the cylinder and 18 indicates the outer plates thereon, the inner plates 17 being secured between the clamping ring 13 and the slid- 25 able clamps 15—16, and the outer plates 18 being secured between the slidable clamps 15—16 and slidable clamps 19 of the ordinary type screw-threaded upon rods 20 rev- 30 olubly mounted in slidable heads 21 which are adapted to be moved inward with the rods 20 and the clamps 19 by means of an eccentric 22 of the well-known type, or in any other suitable manner. Inasmuch as the parts heretofore referred to are well-known in the art and form no part of themselves of my invention,—other than the im- 35 proved clamp 15 of course,—it is believed that it will not be necessary to describe these parts further herein.

Coming now to a description of the clamp 15, 23 indicates the beveled head of said 40 clamp, in the construction shown being formed integrally with the body portion 24 thereof which slides in the usual groove 25 in the surface of the cylinder, being held slidably in said slot by the usual flanges 26.

45 27 indicates a groove in the body of the clamp 15 in which is pivotally mounted, by means of a pivot pin 28, a dog 29, the inner end of which is serrated or toothed as shown in Fig. 2.

50 30 indicates a pin screw-threaded in an opening 31 in the body of the clamp in such position that its inner beveled end is adapted to be screwed down into engagement with the outer end of the dog 29 by means of a 55 wrench or other suitable tool 31 inserted in the outer end of said pin. As will be readily understood, by screwing the pin 30 inward the dog 29 is caused to move in clockwise direction as shown in Fig. 2, bringing the

60 teeth at the inner end of said dog into engagement with the inner face of the groove 25, serving to lock the clamp 15 against movement to the left in Fig. 2. It will be understood, however, that the dog 29 is free to swing still farther in clockwise direction

to permit the clamp 15 to move to the right in said figure.

With a press equipped with my improved clamping means, as soon as the inside plates are obtained from the stereotyping room 70 they are placed in position upon the cylinder and temporarily locked in such position through the medium of the clamp 15, the pressmen being able to rotate the cylinder with one of the plates 17 clamped in position thereon by means of the clamp 15, in order to place the other plates 17 successively in position, without danger of such temporarily-clamped plates becoming loosened or disarranged thereon. Thereafter 80 when the outer plates are obtained from the stereotyping room the pressmen are able to complete the permanent clamping of the plates upon the press in an appreciably shorter time than they would be able to accomplish this task without the use of my improved clamps.

85 The movement of the clamps 15 toward the clamping ring 13, without a loosening of the pin 30 is readily accomplished by 90 reason of the fact that the dog 29 in temporary clamping position stands in a position inclined beyond the center of the pivot pin 28. I do not, however, restrict myself to this detail of construction except as hereinafter specifically claimed.

95 While I have shown the clamp 15 as being capable of being temporarily locked against movement toward the end of the cylinder and away from the clamping ring 100 13, and while that is apparently the preferable form of construction as plate clamping mechanisms are now arranged, I do not restrict myself to this particular arrangement 105 of the clamp 15 except as hereinafter specifically claimed, the essential point being that the clamp is capable of temporarily locking one of the plates in position prior to the final permanent locking of the plates.

110 It will be understood that in the specification and claims I use the term "permanent locking" to denote the locking of the plates for operation of the machine in contradistinction to the temporary locking by means 115 of the clamps 15, and that I do not mean thereby that the plates are adapted to be secured upon the plate support for any particular length of time.

120 What I claim as my invention and desire to secure by Letters Patent is:—

1. The combination of a plate cylinder having a longitudinally-extending groove, a plate clamp mounted in said groove and slidably freely in either direction therealong, locking means adapted to engage one of the longitudinally-extending walls of said groove for holding said clamp against movement in one direction while still permitting movement thereof in the opposite direction, and positively-acting means adapted to en- 125 130

gage said locking means for moving it into operative position.

2. The combination of a plate cylinder having a longitudinally-extending groove, a plate clamp mounted in said groove and slideable freely in either direction therealong, locking means adapted to be projected into engagement with one of the longitudinally-extending walls of said groove for holding said clamp against movement in one direction while still permitting movement thereof in the opposite direction, and a pin having a screw-threaded mounting in said clamp adapted to engage said locking means for 15 moving it into operative position.

3. The combination of a plate cylinder having a longitudinally-extending groove, a plate clamp mounted in said groove and slideable freely in either direction therealong, 20 and rotatably-mounted locking means adapted to be brought by a partial rotation into engagement with said groove at any desired point therealong for holding the clamp non-yieldingly against movement in one direction while still permitting movement thereof in the opposite direction.

4. The combination of a plate cylinder having a longitudinally-extending groove, a plate clamp mounted in said groove and 25 slideable freely in either direction therealong, rotatably-mounted locking means carried by said clamp adapted to be brought by a partial rotation into engagement with said groove at any desired point therealong 30 for holding the clamp against movement in one direction while still permitting movement thereof in the opposite direction, and positively-acting means carried by said clamp for giving said locking means a partial rotation into operative locking position.

5. The combination of a plate cylinder having a longitudinally-extending groove, a plate clamp mounted in said groove and slideable freely in either direction therealong, 45 rotatably-mounted locking means carried by said clamp adapted to be brought by a par-

tial rotation into engagement with said groove at any desired point therealong for holding the clamp against movement in one direction while still permitting movement thereof in the opposite direction, and a pin having a screw-threaded mounting in said clamp adapted to engage said rotatably-mounted locking means for moving it into operative position.

6. The combination of a cylinder having a longitudinally-extending groove, a plate clamp slideably mounted in said groove, a dog pivotally mounted upon said clamp, and positively-acting means adapted to swing said dog on its pivot to bring it into operative engagement with the groove in the cylinder for holding said clamp against movement longitudinally of said groove in one direction.

7. The combination of a cylinder having a longitudinally-extending groove, a plate clamp slideably mounted in said groove, a dog pivotally mounted upon said clamp, and a pin screw-threaded in said clamp adapted to swing said dog on its pivot to bring its projecting end into engagement with one of the walls of the groove in the cylinder to hold said clamp against movement in one direction.

8. The combination of a cylinder having a longitudinally-extending groove, a plate clamp slideably mounted in said groove, a dog pivotally mounted upon said clamp, and a pin screw-threaded in said clamp adapted to swing said dog on its pivot to bring its projecting end into engagement with one of the walls of the groove in the cylinder to hold said clamp against movement in one direction, said dog being adapted to move still further in the direction it is forced by said screw-threaded pin whereby said clamp is permitted a movement in one direction.

WILLIAM EVENSEN.
